EGG GRADING MACHINE

Joshua A. Hill, Canoga Park, Calif.

Application February 23, 1946; Serial No. 649,489

9 Claims. (Cl. 209—121)

1

My invention relates in general to grading machinery or apparatus and, more specifically, to a machine which is particularly adapted for grading ovoid or spherical articles according to the weights thereof. The grading machine disclosed herein incorporates certain improvements on the grading machine disclosed in my copending application, Serial No. 504,226, filed September 29, 1943, which has matured into Patent No. 2,442,689, these improvements being described in detail hereinafter.

The fundamental principles of my invention are particularly applicable to machinery or apparatus for grading eggs and will be described in connection therewith for convenience in disclosing the invention, although it will be understood that these principles are equally applicable to machinery for grading various other articles and that I do not intend to be limited to the specific application disclosed herein.

The conventional practice in grading eggs for market is to separate the eggs into "large," "medium," and "small" sizes according to the weights thereof, some over weight eggs being sold as "extra large" and some underweight eggs being sold as "peewees."

A primary object of my invention is the provision of a machine which will grade a continuous flow of eggs according to the weights thereof in an efficient and completely automatic manner. An important object of my invention is to provide a grading machine which is of simple construction and which may be operated economically.

In general, my grading machine includes a longitudinal main track having a plurality of independent scales aligned therewith, each of which is adapted to remove from the track all eggs of a predetermined minimum weight, and includes a rotatable worm which is adapted to convey a continuous stream of eggs along the track and over the scales, the axis of rotation of the worm being substantially parallel to and preferably being disposed directly above the main track. An important object of my invention is the provision of a conveying worm which includes a spiral strip having forward edge portions which engage the eggs to convey them along the main track, a related object being to provide such a spiral conveyor strip wherein the width of the aforesaid edge portions thereof is considerably less than the diameters of the eggs conveyed thereby. This feature of the construction minimizes friction between the spiral conveyor strip and the eggs due to the presence of foreign matter and thereby minimizes any tendency of the conveyor strip to dislodge the eggs from the track.

2

The scales preferably include track sections which are mounted on pivoted balance arms, and which are aligned with and are normally at the level of the main track, each of the scales being adapted to pivot to dump from the main track all eggs weighing more than a predetermined minimum amount. Another important object of my invention is the provision of scales wherein the track sections move vertically for a substantial distance without rotating as the balance arms pivot, thus insuring accurate weighing of the eggs since the track sections must be depressed by the eggs for an appreciable distance before rotating to dump the eggs. A related object is to provide scales wherein the movement of the track sections is controlled by cam means in a manner such that the track sections move downwardly without rotating for a substantial distance and then rotate very rapidly to dump the eggs after being depressed a predetermined distance.

The grading machine preferably includes a longitudinal feeder track which is aligned with and slopes downwardly toward and joins the main track, and includes gate means for feeding a continuous stream of eggs from the feeder track and onto the main track at predetermined and uniformly spaced intervals. The spiral conveyor strip preferably extends along the inclined feeder track so that as the eggs roll down the feeder track, they engage rearward edge portions of the conveyor strip before rolling onto the main track. Thus, the conveyor strip controls the rate at which the eggs roll down the feeder track, which is another object of my invention.

Still another important object of my invention is the provision of a spiral conveyor strip having an inlet end which is curved inwardly toward the axis of rotation of the spiral strip, the inlet end of the conveyor strip being located above the feeder track adjacent the junction thereof with the main track. This feature of the construction of my grading machine permits rearward edge portions of the inlet end of the spiral conveyor strip to engage any eggs on the sloping feeder track near or slightly above the centers thereof to minimize any tendency for the spiral strips to dislodge the eggs as they roll down the feeder track and onto the main track.

Another object of my invention is the provision of stop means for preventing the presence of more than one egg on each scale at any one time, the stop means preferably comprising a flexible and resilient spiral baffle member which is preferably carried by the spiral conveyor strip. This feature of the construction of my grading machine insures that one and only one egg will be

disposed on each scale at any one time, thereby insuring accurate and reliable weighing operations.

The foregoing objects and advantages of my invention, together with various other objects and advantages thereof which will be apparent hereinafter, may be realized by means of the exemplary embodiment which will be described in detail hereinafter and which is illustrated in the accompanying drawing. Referring to the drawing, which is intended as illustrative only:

Fig. 1 is a plan view of a grading machine which embodies the fundamental principles of my invention;

Fig. 2 is a front elevational view thereof;

Fig. 3 is an enlarged, fragmentary sectional view which is taken along the broken line 3—3 of Fig. 1;

Fig. 4 is an enlarged, fragmentary, end elevational view of cam means for controlling the motion of scale means for weighing articles to be graded;

Fig. 5 is an enlarged, fragmentary, front elevational view of the cam means shown in Fig. 4; and

Figs. 6 and 7 are enlarged, fragmentary, front elevational views illustrating the operation of a portion of the grading machine.

The general construction and operation of the grading machine illustrated in the accompanying drawing are similar to the construction and operation of my prior grading machine which is the subject of my aforesaid co-pending application. Consequently, the present disclosure is primarily concerned with a detailed description of the improvements on my prior grading machine and is not concerned with a detailed description of the remainder of the construction of my present grading machine.

Referring particularly to Figs. 1 and 2, my present grading machine includes a supporting base 10 having main track means or a main track 11 and a feeder track means or a feeder track 12 mounted thereon, the main track including an inlet end 13 and a discharge end 14. The grading machine includes a plurality of scale means 15 for removing from the main track 11 all eggs or other articles weighing more than predetermined minimum amounts, the eggs being conveyed along the main track and over the scale means by worm conveyor means 16 which may be rotated by suitable driving means 17. In order to provide a continuous stream of eggs at predetermined and uniformly spaced intervals, I employ means 18 for feeding a sequence of eggs from the feeder track 12 onto the main track 11, and in order to prevent the presence of more than one egg on any one of the scale means 15, I employ stop means comprising a spiral baffle member 19 which is carried by the worm means 16.

As best shown in Fig. 3, the main track 11 comprises a shallow pan or channel having a pair of upwardly extending edges 20 which form tracks or rails for the eggs or other articles being graded, the eggs being rolled along the rails with the longitudinal axes thereof extending transversely of the rails as indicated by the egg 21. The main track 11, as best shown in Fig. 2, includes a plurality of longitudinally aligned segments 22 which may be mounted on and secured to the base 10 by suitable posts 23 or in any other suitable manner. As will be apparent from Fig. 2, the main track 11 is inclined upwardly from the inlet end 13 toward the discharge end 14 so

that the eggs being graded are held against the worm 16 by the action of gravity. The feeder track 12 is of substantially the same cross-sectional configuration as the main track 11 and is longitudinally aligned therewith, the feeder track being mounted on a sloping block 24 which is mounted on the base 10 so that the feeder track is inclined downwardly toward and registers with the inlet end 13 of the main track. Thus, eggs or other articles which are placed on the feeder track 12 may roll downwardly onto the main track 11.

As best shown in Figs. 1 and 2, the scale means 15 includes three identical scales 26, 27, and 28 which may be adjusted to remove eggs weighing more than progressively smaller minimum amounts from the main track 11, the scales 26, 27, and 28 preferably being adjusted to remove "large," "medium," and "small" eggs from the track, respectively. As best shown in Fig. 3, the scale 26 includes a supporting bracket 39 which carries a knife edge 31, a substantially Y-shaped balance arm 32, best shown in Fig. 1, being balanced on the knife edge. A counterbalance member 33 is adjustably secured to the balance arm 32, rotation of the balance arm in the clockwise direction, as viewed in Fig. 3, being limited by a stop 34. A scale track 36 is pivotally connected to the balance arm 32 at a point 37 which is preferably above the point at which the balance arm is pivoted on the knife edge 31, the scale track being adapted to register with and being adapted for alignment with the track segment 22 there-adjacent as best shown in Fig. 2. Track arms 38 are rigidly secured to and extend downwardly from the scale track 36, a guide roller or cam follower 39 being secured to the track arms. As best shown in Fig. 3, the track arms 38 are preferably inclined downwardly and rearwardly from the pivot point 37 to the guide roller 39, the track arms being inclined downwardly and to the right as viewed in Fig. 3. As best shown in Figs. 4 and 5, the guide roller 39 is movable in a cam slot or guide slot 40 in a guide member 41 to provide cam or guide means for controlling the motion of the scale track 36, the guide member preferably including flanges 41a and 41b interconnected by a base portion 41c which is secured to the supporting base 10 by screws or the like. The guide slot 40 includes a forwardly and downwardly inclined section 40a and a rearwardly and downwardly inclined section 40b, the slot section 40a being defined by cam surfaces 40c and 40d on the flanges 41a and 41b, respectively, in the particular construction illustrated, and the slot section 40b being defined by cam surfaces 40e and 40f on the flanges 41a and 41b, respectively. It will be apparent that the guide slot 40 may be formed in any suitable guide member and I do not intend to be limited to the particular construction shown for the guide member 41.

As best shown in Figs. 3 and 4, the scale track 36, track arms 38, and guide roller 39 will normally be in the positions shown in full lines until depressed by an egg of sufficient weight on the scale track. When an egg of sufficient weight is conveyed onto the scale track 36 by the worm 16 as will be described in detail hereinafter, the forwardly and downwardly inclined section 40a of the guide slot 40 causes the guide roller 39 to move forwardly, as it moves downwardly, into the position shown in phantom and indicated by the numeral 39a in Fig. 4. The forward movement of the guide roller 39 is such that both rails 73 20 of the scale track 36 remain at the same ele-

vation as the scale track moves downwardly into the parallel position shown in phantom in Fig. 3 and indicated by the numeral 36a. The scale track 36 thus moves vertically for a substantial distance before rotating to insure accurate weighing of an egg thereon, particularly if the weight of the egg is close to the minimum weight for which the counterbalance member 33 is set. If the scale track 36 did not move vertically without rotating, the center of gravity of the egg would tend to shift forwardly and away from the counterbalance member 33 as the scale track rotated, thus increasing the rotational moment due to the weight of the egg and causing the egg to be dumped after only a small rotation of the scale track. Thus, the forwardly and downwardly inclined section 40a of the guide slot 40 maintains the moment arm of the egg constant while the scale track 36 moves downwardly for a substantial distance, thus insuring more accurate weighing of the egg than if the scale track began to rotate at the instant it began to move downwardly.

After reaching the position indicated at 39a in Fig. 4, the guide roller 39 enters the downwardly and rearwardly inclined section 40b of the guide slot 40, the slot section 40b preferably, although not necessarily, being substantially horizontal. As the guide roller 39 moves from the position shown in phantom at 39a to the position shown in phantom at 39b at the rearward end of the slot section 40b, the scale track 36 rotates very rapidly about the pivot 37 into the position indicated at 36b to dump the egg from the scale track. Thus, the slot section 40a prevents rotation of the scale track 36 until the egg thereon is accurately weighed, and, if the egg is sufficiently heavy to cause the guide roller 39 to enter the slot section 40b, the latter causes the scale track to rotate rapidly to dump the egg.

The scales 27 and 28 are identical to the scale 26 and include scale tracks 42 and 43, respectively, which are normally aligned with and register with the track segments 22 to complete the main track 11 as best shown in Fig. 2. As best shown in Fig. 1, the counterbalance member 33 of the scale 26, and identical counterbalance members 44 and 45 of the scales 27 and 28 are so positioned that the scales dump eggs weighing more than progressively smaller minimum amounts from the track 11 as more fully described in my aforesaid copending application.

Since the eggs are conveyed along the main track 11 with the longitudinal axes thereof disposed transversely of the track, eggs dumped from the track 11 by the scales 26, 27, and 28 land on end on aprons 46, 47, and 48, respectively. These eggs then roll end-over-end down the aprons 46, 47, and 48 and into compartments 49, 50, and 51, respectively. Any eggs which are underweight, i. e., are too light to be dumped by the scale 28, are conveyed to the discharge end 14 of the track 11 by the worm 16, and roll down an apron 53 into a compartment 54.

The worm 16 includes a shaft 56 which is journaled in bearings 57 above the main track 11 and a portion of the feeder track 12, the bearings being mounted on supporting brackets 58 which are secured to the base 10. The worm 16 is rotated by the driving means 17 as best shown in Fig. 1, the shaft 56 being driven by a motor 59 through a suitable speed-reduction unit 60 and through a sleeve 61 of a suitable flexible material. The worm 16 includes a spiral member 63 of substantial diameter which is rigidly connected to

and is spaced from the shaft 56 by spokes 64, the spiral member being disposed just above and extending along the main track 11 and a portion of the feeder track 12. As more fully described in my aforesaid copending application, the spiral member 63 engages the eggs or other articles to convey them along the track 11 from the inlet end 13 thereof toward the discharge end 14 thereof as the shaft 56 is rotated in the direction of the arrow 65 by the driving means 17.

One of the improvements incorporated in my present invention resides in the fact that the spiral member 63 is in the form of a spiral strip having a forward edge portion 67 which engages the eggs or other articles to be conveyed along the track 11. As best shown in Fig. 6, the width of the edge portion 67 is considerably less than the diameter of an article such as an egg 19 which is engaged and conveyed along the track 11 thereby. The use of the relatively narrow engaging surface provided by the edge portion 67 of the spiral member 63 minimizes friction between the spiral member and the eggs conveyed thereby due to the presence of foreign matter. The use of the narrow edge portion 67 rather than a wide engaging surface has two main advantages in this connection: one main advantage being due to the fact that if dirty eggs are being graded, such a wide engaging surface would tend to guide any loosened dirt down to the eggs, thus creating large frictional forces which would tend to dislodge the egg; and the other main advantage being due to the fact that if the eggs are being graded at temperatures below the prevailing dew point, moisture condenses on the spiral member and would tend to run down such a wide engaging surface to the eggs, thus creating undesirable frictional forces. The use of the narrow edge portion 67 tends to eliminate accumulations of dirt or moisture and thus minimizes any tendency of the spiral member 63 to dislodge the eggs.

Another important improvement incorporated in my present invention resides in the fact that a portion of one of the convolutions forming the spiral member 63 extends along a portion of the feeder track 12 and is of a smaller diameter than the remaining convolutions, thus providing the spiral member with an inlet end segment 69 which is curved inwardly toward the shaft 56, as best shown in Fig. 3. Thus, as best shown in Fig. 6, as an article such as an egg 10 is released by the feeder means 18 and rolls down the inclined feeder track 12, the egg engages a rearward edge portion 71 of the inwardly-curved inlet end segment 69 at a point which is preferably above the center of the egg. This construction substantially eliminates any tendency of the spiral member 63 to knock the egg 10 off the inclined track 12, a tendency which I have found to exist if the inlet end segment of the spiral member initially engages the egg at a point much below the center thereof. As the spiral member 63 continues to rotate from the position shown in Fig. 6 to that shown in Fig. 7, the egg 10 rolls down the feeder track 12 and, in so doing, engages rearward edge portions 71 of the spiral member 63 which are of increasing diameter so that the point of engagement between the egg and the spiral member remains substantially at the center of the egg. The points of engagement between the eggs and the spiral member 63 may be lowered as the eggs are advanced along the track 11, only the initial points of engagement

preferably being substantially at or above the centers of the eggs. Since the egg 70 engages the rearward edge portions 71 of the spiral member 63, the latter serves to control the speed at which the egg rolls down the feeder track 12, which is a feature of my invention.

The feeder means 18 includes a pair of vertically movable horizontal gate members 72 and 73 which are actuated by cams 74 and 75, respectively, on the shaft 56. The cams 74 and 75 are adapted to lift the gate members 72 and 73 to feed a sequence of eggs onto the inlet end 13 of the track 11 at predetermined and uniformly spaced intervals, as described more completely in my aforesaid copending application. The operation of the feeder means 18 is so timed with respect to the position of the inlet end segment 69 of the spiral member 63 that only one egg is disposed between each pair of adjacent convolutions of the spiral member. The timing of the operation of the feeder means 18 is also such as an egg 70 rolls down the feeder track 12 as best shown in Fig. 6, the egg engages the edge portion 71 of the inlet end segment 69 of the spiral member 63, thereby insuring that the extreme end 77 of the inlet end segment does not engage and knock the egg off the track.

The baffle member 19 represents another improvement which is incorporated in my present invention, the baffle member being adapted to keep the egg 68 from rolling onto the scale 26, as best shown in Fig. 7, until an egg 79 already thereon has either been dumped by the scale, or has been moved along the track 11 by the spiral member 63. The baffle member 19 is rigidly secured to the spiral member 63 and is preferably of a spiral configuration so that as the free end 18 thereof disengages the egg 68, the released egg rolls directly onto the scale 26, the baffle member preferably being formed of a flexible and resilient material such as spring wire or the like.

Prior to operating the grading machine, the positions of the counterbalance members 33, 44, and 45, of the scales 26, 27, and 28 are adjusted so that these scales successively dump articles of progressively smaller minimum weights from the track 11. Thus, if the machine is used for grading eggs, the counterbalance members 33, 44, and 45 may be so adjusted that the scale 26 removes large eggs from the track 11, the scale 27 removes medium eggs, and the scale 28 removes small eggs. It will be apparent that the counterbalance members 33, 44, and 45 will all be positioned at different distances from the balance points of the respective scales somewhat as shown in Fig. 1.

In operation, the driving means 17 rotates the worm means 16 in the direction of the arrow 65, the speed of rotation of the worm means preferably being relatively low. The eggs are placed on the feeder track 12 above the feeder means 18 with the longitudinal axes of the eggs oriented transversely of the track. As more fully described in my aforesaid copending application the gate members 72 and 73 of the feeder means 18 cooperate to release a sequence of eggs at predetermined intervals. As each egg is released by the feeder means 18, it rolls down the track 12 and rests against the edge portion 71 of the inlet end segment 69 of the spiral member 63 as indicated by the egg 70 of Fig. 6, the point of initial contact between the edge portion 71 and the egg being at or above the center of the egg because of the inward curvature of the inlet end segment. This construction substantially eliminates any

tendency of the inlet end segment 69 to dislodge the egg 70.

As best shown in Fig. 7, the egg 68, which was released by the feeder means 18 prior to the egg 70, is restrained by the baffle member 19 so that the egg 68 does not roll onto the scale 26 until the previously released egg 79 which is already on the scale 26 is either dumped from the track 11 or is conveyed toward the discharge end thereof by the spiral member 63. When the free end 18 of the baffle member 19 disengages the egg 68, the egg will then roll onto the scale 26 after the previous egg 79 has been removed therefrom.

The scale 26 will remove from the track 11 only those eggs which weigh more than the minimum for large eggs, such large eggs being lowered as the scale track 36 drops and then rotates about the pivot 37 as previously described. The action of the cam roller 39 in the cam slot 40 prevents rotation of the scale track 36 until the scale track has been depressed a substantial distance, thus insuring accurate weighing of the eggs. Since the eggs are disposed transversely of the track 11, they land on end and roll end-over-end down the apron 46 and into the compartment 49. As stated in my copending application, the fact that the eggs are dumped so that they land on end is important in view of the fact that the end portions of the shells of the eggs are considerably stronger than the sides thereof. This feature of my invention substantially eliminates any possibility of breakage as the eggs are dumped from the track 11. It will be apparent that the apron 46 and compartment 49, together with the aprons 47, 48, and 53 and the compartments 50, 51, and 54, may be lined with a suitable material such as felt or the like, if desired, to further reduce any possibility of breakage.

In the event that an egg is too light to be dumped by the scale 26, it is conveyed along the track 11 by the spiral member 63 toward the discharge end 14 of the track. Thus, if an egg weighs less than the minimum weight for which the scale 26 is set but weighs more than the minimum weight for which the scale 27 is set, the egg will not be dumped by the scale 26 but will be dumped by the scale 27, which is identical to the scale 26 except for the relative positions of the counterbalance members 33 and 44. Similarly, if an egg weighs less than the minimum weight for the scale 27 but more than the minimum weight for the scale 28, the egg will not be dumped by either the scale 26 or the scale 27, but will be dumped by the scale 28, which is also identical to the scale 26 except for the position of the counterbalance member 45. Any eggs weighing less than the minimum for which the scale 28 is set will be conveyed to the discharge end of the track 11 by the spiral member 63 and will roll down the apron 53 into the compartment 54.

In conveying the eggs along the track 11 from the inlet end 13 thereof toward the discharge end 14, the spiral member 63 rubs lightly against the eggs substantially transversely of the track because of the relatively small angles between the convolutions of the spiral member and perpendicular to the track as best shown in Fig. 1. This relatively light rubbing action exerts a force component on the eggs in a direction parallel to the track which conveys the eggs gently along the track. The relatively small angles between the convolutions of the spiral member 63 and the track 11, together with the relatively large diameter of the convolutions as compared

to the diameter of the eggs, permits the spiral member to convey the eggs along the track very gently with substantially no possibility of breakage.

The fact that the width of the edge portions 67 and 71 of the spiral member 63 is considerably less than the diameter of the eggs engaged thereby minimizes friction between the spiral member and the eggs as previously described and thus minimizes any possibility of dislodging the eggs from the tracks 11 and 12. I have found that the use of such relatively narrow egg engaging surfaces provides a grading machine which operates more satisfactorily than if wider engaging surfaces were used.

Although I have described the preferred embodiment of my invention and have suggested a specific application thereof to the art of grading eggs, it will be understood that my invention is not to be limited to grading eggs and that various changes, modifications, and substitutions may be incorporated in the preferred embodiment without departing from the spirit of the invention. I hereby reserve the right, therefore, to the protection afforded by the full scope of my appended claims.

I claim as my invention:

1. In an ovoid conveying device, the combination of: track means having an inlet end and a discharge end, said track means being adapted to support and guide an ovoid therealong; rotatable worm means mounted adjacent said track means and adapted to convey an ovoid along said track means from said inlet end thereof toward said discharge end thereof, said worm means including a spiral strip of substantially rectangular cross section having sides which are substantially parallel to said track means and having edges which are substantially perpendicular thereto, the thickness of said strip being substantially less than the diameter of the ovoid; and means for rotating said worm means.

2. In an ovoid grading device, the combination of: track means having an inlet end and a discharge end, said track means being adapted to support and guide an ovoid therealong; scale means aligned with said track means, said scale means being adapted to remove from said track means any ovoid weighing more than a predetermined amount; rotatable worm means mounted adjacent said track means and adapted to convey an ovoid along said track means from said inlet end thereof toward said discharge end thereof and over said scale means, said worm means including a spiral member having an inlet end portion adjacent said inlet end of said track means, said inlet end portion of said spiral member being spaced above said track means at its closest approach thereto a distance at least equal to one-half the diameter of the ovoid, but less than the diameter of the ovoid, and the remaining portions of said spiral member being spaced above said track means at their closest approaches thereto distances not greater than one-half the diameter of the ovoid; and means for rotating said worm means.

3. In an ovoid grading device, the combination of: track means having a downwardly sloping inlet end and a discharge end, said track means being adapted to support and guide an ovoid therealong; scale means aligned with said track means, said scale means being adapted to remove from said track means any ovoid weighing more than a predetermined amount; rotatable worm

means mounted adjacent said track means and adapted to convey an ovoid along said track means from said inlet end thereof toward said discharge end thereof and over said scale means; a helical baffle carried by and coaxial with said worm means, said helical baffle extending toward said discharge end of said track means and being adapted to prevent the presence of more than one ovoid on said scale means at any one time; and means for rotating said worm means.

4. In an ovoid conveying device, the combination of: track means having a downwardly inclined inlet end portion and having a discharge end portion, said track means being adapted to support and guide an ovoid therealong; rotatable worm means including a spiral member having forward and rearward ovoid-engaging surfaces, said worm means further including a shaft and means connected to said spiral member in a zone intermediate and spaced from said ovoid-engaging surfaces for connecting said spiral member to said shaft, whereby to render said ovoid-engaging surfaces free from obstructions, said forward ovoid-engaging surface being adapted to engage and convey an ovoid along said track means toward said discharge end portion thereof, and said rearward ovoid-engaging surface being adapted to control the rate at which an ovoid rolls down said inclined inlet end portion; and means for rotating said worm means.

5. In an egg-weighing device, the combination of: a balance arm pivoted on a main pivot point; an egg receiving track pivotally connected to said balance arm by a track pivot on one side of said main pivot point; a counterbalance member on said balance arm on the other side of said main pivot point; and guide means for controlling rotation of said track about said track pivot point in response to rotation of said balance arm about said main pivot point so that said track moves vertically for a substantial distance between parallel positions, said guide means including a cam surface which is inclined downwardly and outwardly with respect to said main pivot point, and including a cam follower which is movable along said cam surface.

6. In an egg-weighing device, the combination of: a balance arm pivoted on a main pivot point; an egg receiving track pivotally connected to said balance arm by a track pivot on one side of said main pivot point; a counterbalance member on said balance arm on the other side of said main pivot point; a cam follower on said track; and a guide member having a slot therein for said cam follower, said slot including a portion, which is inclined downwardly and outwardly relative to said main pivot point, said cam follower being adapted to move in said outwardly and downwardly inclined portion of said slot to cause said track to move parallel to itself for a substantial distance.

7. In a weighing device, the combination of: a balance arm pivoted on a main pivot; a scale platform pivotally connected to said balance arm on one side of said main pivot; a counterbalance member on said balance arm on the other side of said main pivot; a platform arm depending from said scale platform; and guide means for initially moving the lower end of said platform arm outwardly away from said main pivot as said scale platform moves downwardly upon rotation of said balance arm about said main pivot and for subsequently moving the lower end of said platform arm inwardly.

8. In an ovoid conveying device, the combina-

tion of: track means adapted to support and guide an ovoid and having a downwardly inclined inlet end portion; a rotatable worm positioned above and substantially parallel to said track means and adapted to convey the ovoid therealong, said worm having an inlet end portion which is positioned above said downwardly inclined inlet end portion of said track means and which is of a smaller diameter than the other portions of said worm, said inlet end portion of said worm being of such diameter that it clears said track means by a distance which is equal to at least one-half the diameter of the ovoid, but less than the diameter of the ovoid, and said other portions of said worm being of such diameters that they clear said track means by distances not greater than one-half of the diameter of the ovoid; and means for rotating said worm.

9. In an ovoid conveying device, the combination of: track means adapted to support and guide an ovoid and having a downwardly inclined inlet end portion; a rotatable worm positioned above and substantially parallel to said track means and adapted to convey the ovoid therealong, said worm having an inlet end positioned above said downwardly inclined inlet end portion of said track means, and having forward and rearward ovoid-engaging surfaces, said forward ovoid-engaging surface being adapted to convey an ovoid along said track means away from said inlet end portion thereof, and said rearward ovoid-engaging surface being adapted to control the rate at which an ovoid rolls down said inclined inlet end portion of said track means; means for feeding a sequence of ovoids onto said inclined inlet end portion of said track means, said

feeding means including a gate which is movable to an open position to feed an ovoid onto said inclined inlet end portion of said track means, and including a cam on said worm for moving said gate to said open position, said inlet end of said worm leading said cam so that each ovoid is fed onto said inclined inlet end portion of said track means after said inlet end of said worm has passed the line of said track means, whereby the ovoid rolls down said inclined inlet end portion into engagement with said rearward ovoid-engaging surface; and means for rotating said worm.

JOSHUA A. HILL.
